(57) **CLAIM**

The ornamental design for a computer screen with a graphical user interface, as shown and described.

DESCRIPTION

FIG. 1 is a front view showing a first image of a computer screen with a graphical user interface;

FIG. 2 is a front view showing a second image thereof;

FIG. 3 is a front view showing a third image thereof;

FIG. 4 is a front view showing a fourth image thereof;

FIG. 5 is a front view showing a fifth image thereof; and,

FIG. 6 is a front view showing a sixth image thereof.

The outermost broken line in each figure shows a computer screen and forms no part of the claimed design. The other broken lines show portions of the graphical user interface and form no part of the claimed design. The graphical user interface sequentially transitions between FIGS. 1-6.
